Carl A. Baer, New York, N. Y.

Application March 31, 1939, Serial No. 265,072

11 Claims. (Cl. 229—62)

This invention relates to envelopes or containers usually of envelope shape and of the type adapted to contain commodities. More particularly, the invention relates to the production of an improved tobacco pouch which may be employed in the packaging of tobacco products by the manufacturer or packer thereof and which will preserve the odor and taste-imparting constituents of the tobacco in a fresh condition.

It has heretofore been proposed to provide a tobacco pouch which will serve as a package or container in which the tobacco may be dispensed as by the retailer and which will also serve as a pouch for use by the purchaser during the period the tobacco is being consumed.

The primary object of this invention is to provide a flexible container of an inexpensive but durable moistureproof and greaseproof material which cannot easily be torn, fractured or perforated and which will serve as a pouch for the packaged material from the time the container is filled until the contents are ultimately consumed though this be in small increments.

Another object of the invention is an envelope container of the character described which can be permanently sealed along the side edges and temporarily sealed at the mouth so that the mouth may be opened and the container used as a pouch without destruction of the material of which the envelope container is made. In carrying this aspect of the invention into effect, there is utilized a sheet or layer of thermoplastic material of such characteristics that juxtaposed surfaces of the material may be caused to be joined by merger of the material by the application of relatively high temperature and low pressure and which merged material cannot be separated except by disruption of the material, while, by the application of relatively lower temperature but relatively higher pressure than is required to cause the merging of the material, juxtaposed surfaces of the material may also be caused to adhere superficially with an autogenous bond separable in the plane of contact of the original surfaces. In some situations, predetermined portions of said sheet or layer are so superficially adhered and in other situations in addition thereto other portions of said sheet or layer are joined by merger of said material. Other aspects of the invention contemplate the lamination of fibrous material such as paper or sheet metal, such as foil, which may be laminated with or coated with the aforesaid thermoplastic material. In still other situations, lamination of metal, fibrous material and foil may be availed of.

In one embodiment of the invention, one end of a generally rectangular strip of material is folded back upon itself to form the container portion of the pouch. The side edges of this container portion are permanently adhered together

preferably by regulated heat and pressure, the thermoplastically cohesive qualities of the lining material being availed of for this purpose. After the contents have been introduced, the mouth of the container is similarly sealed or caused to temporarily adhere together also by regulated heat and pressure of a different order from that utilized along the side edges usually higher pressure and lower temperatures.

10 The invention also seeks a pouch or container which is ornamental and practical from the standpoint of ease and cheapness of manufacture and durability and flexibility in use.

This invention provides a container comprising 15 a sheet one side of which carries a layer of normally lubricous but thermoplastically cohesive material to serve as a liner for the container folded to form a receptacle with edges arranged to position the thermoplastically adhesive layer 20 face to face and serve as closures for the container.

Further provided by this invention is a container comprising a sheet, carrying on one face a layer of normally lubricous but thermoplastically cohesive material to serve as a liner for the container, one section of which is folded back on itself to form a pocket with the layer of material on the inside, the two edges of the pocket ending at the fold and the edge between these two edges being sealed by the cohesive action of the layer of thermoplastically cohesive material the seal along one of said edges being relatively weaker than the others.

An important feature of this invention resides 35 in providing a container comprising a sheet, one side of which is adhered to a layer of normally lubricous but thermoplastically cohesive material to serve as a liner for the container, folded to form a receptacle with edges arranged to position the thermoplastically cohesive lining layer 40 face to face and sealed to itself, at least one of said seals serving as the mouth of the container being weaker than the bond between the lining layer and the sheet.

45 These and other objects of the invention and the means for their attainment will be more apparent from the following detailed description taken in connection with the accompanying drawings illustrating one embodiment by which 50 the invention may be realized and in which:

Figure 1 is a view in plan showing the invention embodied in a tobacco pouch illustrated in open position, that is, with the flap of the envelope in prolongation of the container portion;

55 Figure 2 is a transverse sectional view of a filled and closed pouch;

Figure 3 is a view in elevation showing diagrammatically a sealing device;

Figure 4 is a sectional partially exploded view 60 along the lines 4—4 of Figure 1;

Figure 5 is a front perspective view showing a modified form of container;

Figure 6 is an enlarged fragmentary horizontal section along the line 6-6 of Figure 5;

Figure 7 is a front perspective view similar to Figure 5 after folding; and

Figure 8 is a top plan view of Figure 7.

To construct a container or pouch of the type shown in Figures 1 and 2, a rectangular strip or sheet of moisture-proof material, hereinafter more specifically described, is, as shown in Figure 1, folded on a transverse line 8 substantially one-third the distance between the ends of the strip so that the lower third or section 7 of the strip is folded back upon section 9. Sections 7 and 9 may, when secured along their side edges 13 and 15, form a pocket and the upper section 11 may be folded down upon the section 7 as a flap to close the mouth of the same as is common in envelopes and tobacco pouches.

The sheet of moisture-proof material of which the pouch is made may take any convenient form although in the embodiment illustrated in Figure 1 it is shown as comprising an intermediate sheet 17 which may conveniently be of fibrous or cellulosic material such as tissue paper. The outer surface of the sheet may be covered by an adhered lamination of a metallic nature such as indicated at 19 to add strength and improve the appearance of the package as well as serving in other important ways. On the opposite side of the sheet 17 from the impervious sheet 19 is a lining 21 which is preferably thermoplastically cohesive such as a rubber hydrohalide. This may be the rubber hydrohalide commercially known as "Pliofilm" adhesively applied, for instance, as a preformed layer on the surface of the sheet 17.

While rubber hydrohalide is mentioned as a suitable material for the purpose, it is to be understood that other normally lubricous non-tacky thermoplastically cohesive materials may be applied either as a preformed layer or a coating so that when two layers are juxtaposed by the overlapping of the part 7 on the part 9, the two edge portions 13 and 15 may be caused to adhere by the application of heat and pressure. Such material 21, however, must be so selected that at normal temperatures it is not tacky. For the constructional details only the free edge portions 13 and 15 of the sections 7 and 9 need be provided with such a thermoplastic material. It will be appreciated that in the interest of quantity production and increasing the protection to the contents it is desirable that the entire sheet be coated with the thermoplastically cohesive material in order that blanks of the shape of the combined sections 7, 11, 9 may be cut therefrom.

It is desirable and, in fact, contemplated by the present invention that the side edges 13, 15 of the sections 7 and 9 shall be permanently adhered together to form the receptacle. This is accomplished by placing these side edges between platens, at least one of which is heated and pressing the edges together by the application of pressure until the application of such regulated heat and pressure seals these sides with a permanent seal and the side edges of the sheet 7 and 9 cannot be separated without destroying the material of which the sheet is formed, that is, without actually tearing the material including layers 17 and 19.

On the other hand, it is desirable after the pouch is filled with tobacco or other product 27 by the manufacturer or packer, that a moisture-

proof mouth seal be provided along the edge 23 of the portion 7 to seal the same to the portion 9 so long as the container is on the dealer's shelf, but this seal at the edge 23 must be such that it can be opened to provide access to the contents of the pouch without damaging the envelope. It will be obvious that in opening the mouth at the edge 23, the seal there must be of a temporary nature so that it can be opened by the purchaser without destroying the sheet material 17-21. Such temporary seal is accomplished in substantially the same manner as that for sections 13 and 15, but by the application of greater pressure than that used to seal the side edges 13 and 15 and the use of less heat. Once opened, however, the material 21 at this point is not tacky or adhesive but remains as an impervious layer so that the packaged materials flowing through the mouth will not adhere to the layer 21.

It will thus be seen that the pouch so provided is such that the contained tobacco or other commodity will be kept fresh for an extended period of time, so that the retailer may keep an ample supply of tobacco on hand without its becoming stale and dry, as is the case with tobacco packed in tin cans and ordinary bags. When the purchaser desires access to the contents of the pouch, lip 23 at the seal line may be readily separated from the inner surface of the parts 9 and 11 to break the mouth seal thus permitting the desired quantity of the contents to be removed through the mouth of the pouch; thereafter this mouth will not seal but the pouch may be used as any common tobacco pouch by folding down the flap 11 over the portion 7 to close the mouth.

It has heretofore been proposed to form a seal at the mouth by coating the adjacent area with a liner which is normally both adhesive and cohesive. These surfaces then required treatment by a powder such as one comprising a starch whereby the surfaces will not be tacky to the touch. Experience has shown that such a powder covered surface for the tobacco pouch has not found favor with the public due in part to the fact that the effect of the powder is temporary and particles of the tobacco adhere to the lining to the annoyance of the user. Furthermore, containers provided with a complete coating of an uncured rubber dusted with powder on the interior surface was not moistureproof and the contents quickly dried out.

With the pouch of this invention escape of the material is not usual because the closure flap may be wrapped around the body portion of the pouch and, as the contents are removed, the flap may be folded over along a line as low as or below the mouth.

In the embodiment of the invention as illustrated in Figures 1 and 2, the material from which the container is constructed comprises three principal layers. These are, respectively, the metal foil 19 which is adhered by a resinous type of adhesive to a supporting layer of paper or the like 17 in turn adhered to the moistureproof thermoplastic layer 21 by another adhesive which may be a latex adhesive for a Pliofilm layer. In such a construction, the outer metal foil layer provides a protective surface which can be embossed, printed, or otherwise embellished with various decorative features. In addition to improving the appearance of the container ultimately constructed, the metal foil on the outside adds substantial structural strength to the sheet of material. However, since it is usually prefer-

able to employ a relatively thin layer of foil, some support must be given to this foil. The amount of support is dependent upon a number of factors as is also the character of the support. For example, where the foil is of extreme thinness, as on the order of four ten thousandths of an inch, considerable support is necessary, while on the other hand, if the foil is of a thickness of about one thousandth of an inch, less support is necessary. In the first instance, it is usually desirable to interpose a layer of paper. This may be bleached kraft, sulfite, jute tissue, pre-glassine or a twist tissue. Pre-glassine is that form of paper which is prepared for the manufacture of glassine papers involving processing in a high pressure calender. This processing may be omitted when the paper is employed in the present construction where transparency is not necessary. In some constructions, particularly those omitting the metal foil the entire sheet may be transparent.

This intermediate layer of paper is adhered to the metal with a suitable adhesive which may be any of the well known types that may or may not be applied with a solvent or on the other hand, may include a thermoplastic type of adhesive. Various adhesives are known for adhering paper to metal. It will thus be seen that one of the first operations in the preparation of one of the materials for the manufacture of the container forming the subject matter of this invention is the adherence of the outer metal foil to a supporting layer of paper with an adhesive. After this laminated sheet has been prepared, the paper is adhered to a film or layer which is normally non-tacky but which can be made adhesive or cohesive by the application of heat and pressure. In one of the preferred embodiments of the invention, the inner layer is a rubber hydrohalide of the type commercially known as Pliofilm. This is generally manufactured as a continuous film and a sheet of Pliofilm is adhered to the paper usually after it carries the foil with a suitable adhesive. A latex adhesive is useful for this purpose. It is also proposed that instead of precasting a sheet of Pliofilm and adhering such sheet to the paper that the rubber hydrohalide be applied directly to the paper from a solution or by molten application.

In the manufacture of a container which is made of a laminated material having three layers of the type above described, the paper serves particularly to add body and feel to the material but also serves the function of assisting in the adhesion between the inner thermoplastic layer and the metal. Some thermoplastic layers can be applied to the metal directly but as a general rule it has been found preferable to interpose the layer of paper which can then be adhered to the metal and in turn to the inner layer.

On the other hand, where a heavier sheet of metal foil is employed, the inner layer may be applied directly to the metal foil either by its own adhesiveness or by the interposition of an additional adhesive which provides a bond between the metal and the inner film. Of this type is the laminated sheet in which a coating of a rubber hydrohalide is cast directly on the metal without an adhesive. In all cases where a metal foil is employed, it is preferably an annealed foil.

Instead of constructing the laminated sheet in the manner above described by including a film of a rubber hydrohalide other thermoplastic coat-

ings may be substituted. For example, it is possible to use a resinous material which may, if desired, be precast as a sheet and then adhered to the paper layer.

Considered generally, the inner layer of the ultimate container should be a material which is preferably odorless and which has a relatively smooth lubricous nonadhesive surface at the normal temperature to which the package will be exposed in order that there will be no adherence between the contents of the package and the inner lining or layer. On the other hand, this inner layer or lining must have the property of adhesiveness under elevated temperatures or at high pressures or a combination of both and should preferably be effected by them so that it will selectively bond with itself with different degrees of adhesiveness under varying temperature and pressure combinations. It has been found that the rubber hydrohalide, such as is commercially known as Pliofilm, possesses these properties and it has also been found that other materials may be employed including alkyd resins, the phenol aldehyde resins, vinyl resins and other similar resinous materials as well as certain cellulose derivatives including the cellulose esters, and cellulose ethers when properly plasticized with selected plasticizers in suitable amounts. As in the case of the rubber hydrohalide, these other materials may be applied as preformed films or cast directly on the base of either paper or metal.

Another material which has been found suitable for the construction of containers according to the teachings of this invention, is a parchment type of paper base coated on one or both sides with a layer of rubber hydrohalide such as that commercially known as Pliolite or other lubricous thermoplastic layer. Another suitable material comprises two independent sheets of a glassine type of paper with a nitrocellulose coating on each side of such sheets, the two sheets being cemented together with a suitable adhesive. This construction which includes a nitrocellulose coating on both exposed faces is a plasticized nitrocellulose with thermoplastic properties so that a container may be constructed in accordance with the teachings of this invention by the application of heat and pressure along those edges which are to be joined. It is also possible to embody the teachings of this invention in a container in which the supporting sheet is made from the material known as Cellophane provided with a coating on at least one side which is non-adherent to itself but thermoplastically cohesive. The foregoing construction would be transparent, semi-transparent or opaque as determined by the selection of materials.

In another construction, an inner layer of opaque or semi-opaque material such as paper is first printed on what will be the exposed surface and then this exposed surface is coated with a transparent layer or film applied either as a coating or an overlaid sheet. This coating or overlaid sheet may be Cellophane, a transparent lacquer, Pliofilm, or the like. In this manner the printing on the intermediate sheet is visible on the outside of the package and presents a smooth appearance. There will, of course, be attached to the inner side of the intermediate layer a coating or film of the types described which is thermoplastically cohesive.

In a continuous method for preparing a container of the type illustrated in Figures 1 and 2, the laminated sheet is made up in long rolls which

have a width comparable to the combined sections 7, 9 and 11. As the sheet is withdrawn from the roll, one edge is first folded over to form the pocket by the fold along the line 8 in Figure 1. When the fold has been completed, the web is passed between heated members which can apply heat and pressure, along the sections 13 and 15 but these members for applying heat and pressure will be twice the width of the sections indicated in order that adjacent containers will also be adhered together. After passing from the members which apply the heat and pressure, suitable cutters are provided which sever the containers along the line about midportion of the adhered sections 13 and 15 between adjacent containers. In one of the preferred methods for constructing containers according to the teachings of this invention, there is provided suitable members rotated about parallel shafts one of which has a neoprene surface heated to a temperature of about 150° F. and the other a metal surface heated to about 300° F. These members engage the sections 13 and 15 and apply the necessary heat and pressure for providing adhesiveness between the inner layers. It will be evident, of course, that the exact temperatures employed will depend upon the physical characteristics of the lining material and should produce a bond as strong or stronger than the bond between the lining and its support.

It will also be understood that instead of adhering the lining materials by the application of heat and pressure that it would be possible to apply a small amount of solvent along the edges desired to be sealed and then pressing the edges together. This procedure is recommended when the containers are in effect made individually.

In the container construction of Figures 1 and 2 it will be noted that only one surface of the sheet need be provided with the thermoplastic coating since all of the closures are between the same faces. This feature of the invention may be embodied in a container construction as is illustrated in Figures 5 to 8, inclusive. As shown in Figure 5, the sheet 38 provided on the interior surface with a normally lubricous but thermoplastically cohesive layer 32 is formed from a continuous sheet shaped into the form of a cylinder and the adjacent edges of the sheet 34 and 36 brought into juxtaposition with the edge portions of the inner surface 32 in contact. Heat and pressure is applied along these edges to form a cohesive union between the same face of the sheet as brought together. This may conveniently be accomplished on a continuous machine which gradually shapes the web of paper into generally cylindrical forms after which it is passed between heated rollers which will apply the heat and pressure necessary to form the seal between the edges 34 and 36. Members such as 50 and 52 of Figure 3 with heating elements 53 and 54 may be employed for this purpose. After the joint has been formed, the cylinder may be folded in any manner, as for example, that illustrated in Figures 7 and 8 wherein the joint is put on the center of one face and permanent creases or folds provided along the edges 38 and 40. One end 42 may, if desired, be closed during original operation as by the application of heat and pressure and the other end may be left open for filling. After the receptacle has been filled, its closure is obtained by the application of heat and pressure along that edge. Such application of heat and pressure may be with smooth sur-

faces or an irregular roller may be employed which produces some embossing action.

With the construction such as shown in Figures 1 and 2 as well as in Figures 5 to 8, inclusive, it will be evident that where the lining material 32 is of a moistureproof character, the receptacle will retain the contents thereof in their fresh condition.

10 The use of an outer foil produces an opaque package preventing deterioration of the contents caused by exposure to light and also preserves the characteristics of the other laminations which were subject to the influence of light.

15 The embodiment of the invention illustrated in Figures 1 and 2 is particularly designed for use as a container to distribute pipe tobacco. With this construction, the seal 23 is of a different type than the seals along the edges 13 and 15 and may preferably be slightly in from the extreme 20 edge of the section 1 in order that when the user desires to open the mouth and expose the contents, he may have a short area which may be grasped by the fingers to be pulled to break the seal. This cohesive seal at the mouth should be 25 weaker than the bond between the lining and its support. When the seal is broken the severance should be between the two layers of adhered lining without plucking from either layer to preserve the liner.

30 As illustrated in Figure 2, after the tobacco or other product has been inserted into the envelope, the mouth is sealed as indicated at 23 and the flap section 11 folded over. This flap may be of a size comparable to the envelope itself or 35 may be of a smaller size depending upon the ultimate purpose. In the case of a tobacco pouch, however, this is preferably of such a size that when the pouch is folded just below the final or mouth seal 23, the flap will cover one complete 40 side and also pass around to the back surface. It may be held in this position by a seal such as the revenue stamp 25 commonly used for tobacco products.

Various modifications will occur to those skilled 45 in the art in the composition of the sheet material of which the pouch is manufactured as well as in the configuration and disposition of the component parts thereof and no limitation is intended by the phraseology of the foregoing 50 specification or illustrations in the accompanying drawings except as indicated in the appended claims.

As previously pointed out in the specification, the sheet of material of which the envelope is 55 fabricated may take any convenient form and, where it includes one or more backing sheets of paper, foil or other material, the innermost of such backing sheets may be wholly covered by a film of thermoplastic material, or its free edges 60 or other selected areas only provided with film-like coverings of such material. The term "sheet material" which appears in the appended claims is broadly descriptive of the various constructional forms of the material of which the envelope 65 may be fabricated.

What is claimed is:

1. A hermetically sealed envelope comprising a rectangular sheet of metal foil provided with a film of rubber hydrochloride secured to one face thereof, substantially one third of said sheet being laterally folded upon the adjacent portion in edge coinciding relation with said film on the inside, said opposite coinciding edge portions being permanently sealed together by means of pressure applied at a temperature sufficiently

high to cause merger and permanent union of the films, and a zone adjacent the free edge of said folded portion but spaced therefrom being superficially sealed by means of pressure applied at a temperature below the temperature causing merger and permanent union of the films, said zone extending from one permanently sealed edge to the other and said films at said zone being readily manually separable in the plane of contact of the joined surfaces.

2. A method of forming a hermetically sealed envelope comprising, securing a film of rubber hydrochloride to one face of a rectangular sheet of metal foil, laterally folding substantially one third of said sheet upon the adjacent portion in edge coinciding relation with said film on the inside, applying sealing pressure throughout the opposite coinciding edge portions at a permanent sealing temperature, said temperature being sufficiently high to cause merger and permanent union of the films and applying sealing pressure to a zone of said folded portion adjacent to the free edge thereof but spaced therefrom and extending from one permanently sealed edge to the other, the last named sealing pressure being applied at a temperature below the permanent sealing temperature whereby a superficial bond is formed which is readily manually separable in the plane of contact of the joined surfaces.

3. An envelope of sheet material completely enclosing a space for the storage of material such as tobacco, contiguous portions thereof bordering said space being film-like and fabricated of rubber hydrochloride, selected areas of the contiguous portions of said sheet material bordering said storage space being permanently sealed together by means of pressure applied at a temperature sufficiently high to cause cohesion and permanent union thereof, and the remaining areas of such contiguous portions being superficially sealed by means of sufficient pressure applied at a temperature below the temperature causing cohesion and permanent union, the superficially sealed adhering areas of said contiguous portions being readily separable manually without injury to either to permit access to the material storage space.

4. An envelope of sheet material completely enclosing a space for the storage of material such as tobacco, contiguous portions thereof bordering said space being film-like and fabricated of vinyl resin, selected areas of the contiguous portions of said sheet material bordering said storage space being permanently sealed together by means of pressure applied at a temperature sufficiently high to cause cohesion and permanent union thereof, and the remaining areas of such contiguous portions being superficially sealed by means of pressure greater than that necessarily used in producing the permanent seal and applied at a temperature below the temperature causing cohesion and permanent union, the superficially sealed adhering areas of said contiguous portions being readily separable manually without injury to either to permit access to the material storage space.

5. An envelope of sheet material completely enclosing a space for the storage of material such as tobacco, contiguous portions thereof bordering said space being fabricated of paper coated with a film of plasticized nitrocellulose having thermoplastic properties, selected areas of the contiguous portions of said sheet material bordering said storage space being permanently sealed together by means of pressure applied at a

temperature sufficiently high to cause cohesion and permanent union thereof, and the remaining areas of such contiguous portions being superficially sealed by means of sufficient pressure applied at a temperature below the temperature causing cohesion and permanent union, the superficially sealed adhering areas of said contiguous portions being readily separable manually without injury to either to permit access to the material storage space.

6. An hermetically sealed envelope of sheet material completely enclosing a space for the storage of commodities such as tobacco, contiguous portions thereof bordering said space being film-like and fabricated of material free from tackiness at normal atmospheric temperatures and having such thermoplastic cohesive properties that they may be selectively bonded together either permanently or superficially by the application of varying degrees of heat and pressure, selected registering areas of the contiguous portions of said sheet material bordering said storage space being bonded together so as to form a permanent hermetic seal by the application of pressure while said areas are heated to a temperature sufficiently high to cause cohesion and permanent union thereof, the remaining areas of said portions being bonded together so as to form a separable superficial hermetic seal for the envelope by the application of sufficient pressure, applied at a temperature below the temperature causing cohesion and permanent union of the film-like portions, whereby said portions may be readily manually separated without injury to either to permit access to the material storage space.

7. The method of forming a hermetically sealed envelope for material such as tobacco comprising shaping sheet material which is free from tackiness at normal atmospheric temperatures and which has such thermoplastic cohesive properties that it may be selectively bonded together either permanently or superficially by the application of heat and pressure in such manner as to define a wholly enclosed material storage space with portions thereof bordering said space in contiguous relationship, permanently sealing certain areas of said contiguous bordering portions by pressing said areas together while heated to a temperature sufficiently high to cause cohesion and permanent union thereof, and superficially sealing the remaining areas of said contiguous portions by the application of sufficient pressure at a temperature below the temperature causing cohesion and permanent union of the film-like portions, thus producing surface adhesion but not cohesion and permanent union, the adhesive-joined areas being readily manually separable without injury to either to permit access to the material storage space.

8. An hermetically sealed envelope of sheet material completely enclosing a space for the storage of commodities such as tobacco, contiguous portions thereof bordering said space being film-like and fabricated of material free from tackiness at normal atmospheric temperatures and having such thermoplastic cohesive properties that they may be selectively bonded together either permanently or superficially by the application of varying degrees of heat and pressure, a permanent hermetic seal being effected when said film-like portions are pressed together while heated to a temperature sufficiently high to cause cohesion and permanent union thereof, the contiguous portions of said sheet material bordering said storage space, or selected areas thereof, be-

ing bonded together so as to form a separable superficial hermetic seal for the envelope by the application of sufficient pressure, applied at a temperature below the temperature causing cohesion and permanent union of the film-like portions, whereby said portions may be readily manually separated without injury to either to permit access to the material storage space.

9. The method of forming an hermetically sealed envelope for material such as tobacco comprising shaping sheet material which is free from tackiness at normal atmospheric temperatures and which has such thermoplastic cohesive properties that it may be selectively bonded together either permanently or superficially by the application of heat and pressure in such manner as to define a wholly enclosed material storage space with portions thereof bordering said space in contiguous relationship, and superficially sealing said portions, or selected areas thereof, by the application of pressure sufficient, at a temperature below the temperature causing cohesion and permanent union of the film-like portions, to produce surface adhesion but not cohesion and permanent union thereof, said portions, or the areas thereof thus caused to adhere being readily manually separable.

10. A method of forming an hermetically sealed envelope comprising securing a film of a vinyl resin to one face of a rectangular sheet of metal foil, laterally folding substantially one-third of said sheet upon the adjacent portion in edge-coinciding relation with said film on the inside, applying sealing pressure through the opposite coinciding edge portions at a permanent sealing temperature, said temperature being sufficiently high to cause merger and permanent union of the films and after filling said envelope applying

sealing pressure to a zone of said folded portion adjacent to the free edge thereof but spaced therefrom and extending from one permanently sealed edge to the other, the last-named sealing pressure being applied at a temperature below the said permanent sealing temperature whereby a superficial bond is formed which is readily manually separable in the plane of contact of the joined surfaces.

- 10 11. An hermetically sealed envelope of sheet material completely enclosing a space for the storage of commodities such as tobacco, contiguous portions thereof bordering said space being film-like and fabricated of material free from tackiness at normal atmospheric temperatures and having such thermoplastic cohesive properties that they may be selectively bonded together either permanently or superficially by the application of varying degrees of heat and pressure,
- 15 20 selected registering areas of the contiguous portions of said sheet material bordering said storage space being bonded together so as to form a permanent hermetic seal by the application of pressure while said areas are heated to a temperature sufficiently high to cause cohesion and permanent union thereof, the remaining areas of said portions being bonded together so as to form a separable superficial hermetic seal for the envelope by the application of pressure greater than
- 25 30 the pressure utilized when said cohesion and permanent union of the film-like portions is being effected, applied at a temperature below that to which said film-like portions are raised when said permanent union is being effected, whereby said portions may be manually separated without injury to either to permit access to the material storage space.

CARL A. BAER.
